UNITED STATES PATENT OFFICE.

XIMENA McGlashan, LEONORA G. McGlashan, AND CHARLES F. McGlashan, OF TRUCKEE, CALIFORNIA.

ENTOMOLOGICAL MOUNT.

1,151,280.

Specification of Letters Patent. Patented Aug. 24, 1915.

Application filed September 8, 1914. Serial No. 860,590.

To all whom it may concern:

Be it known that we, XIMENA McGlashan, LEONORA G. McGlashan, and CHARLES F. McGlashan, all citizens of the 5 United States, residing at Truckee, in the county of Nevada and State of California, have invented new and useful Improvements in Entomological Mounts, of which the following is a specification.

10 This invention relates to card mounts for entomological specimens and the like, and in particular to improvements over our former patent entitled "Entomological mount" issued July 21, 1914, #1,104,371.

15 The main object of the present invention is to provide new and novel means for supporting the specimen within the mount.

Further objects will hereinafter appear.

The invention consists of the parts and 20 the combination and construction of parts hereinafter more fully described and claimed, having reference to the accompanying drawings, in which—

Figure 1 shows the application of the 25 invention. Figs. 2 and 3 are perspective views of the card mounts. Fig. 4 is a cross section on line 4—4, Fig. 1. Fig. 5 is a perspective view showing the preferred form of pin. Fig. 6 shows a slight modification of same. Fig. 7 shows the jewelry mount. Figs. 8 and 9 show other modified forms of pins.

Our invention consists of a card mount 30 for entomological specimens, natural history and other exhibits, and comprises in this instance the cards 2 and 3, of paste-board or like material, in which are formed registering openings 4 of suitable shape. The specimen to be exhibited is adapted to be 40 mounted in the space formed by these registering openings and is in the present instance supported as follows:

Referring to Fig. 5, A indicates an entomological pin which consists of a piece of 45 wire shaped substantially as a hair pin. It consists of the parallelly disposed legs 5 and 6 joined at the base and terminating in sharp points 7 bent inward at right angles, or the pin may be constructed in separate 50 sections 5^a and 6^a, as shown in Fig. 2. The pins thus constructed are preferably secured to one or both of the card sections by a strip of gummed paper 8 as shown in Figs.

2 and 3, or in any other suitable manner, and is then ready to receive and support 55 the specimen to be mounted.

When mounting the specimen it is only necessary to force the points 7 of the pin into the body portion of the same. It will thus be securely fastened and retained in a 60 fixed position approximately central of the registering openings. The legs of the pin will further assist to support the specimen as they press the wings firmly against the superimposed glass plate. A pair of glass 65 plates 9 and 10 may then be placed exterior of the card sections to form a transparent closure for the registering openings in the cards wherein the specimen is mounted, and the whole, that is, the cards and glass plates, 70 may be secured together by a tape or binding strip 11 applied around the edges, as shown in Figs. 1 and 4.

The card-board sections may be embossed and appropriately embellished in such a 75 manner that the finished mount presents the general appearance of a postal card or ordinary photograph card, with an opening therein in which the specimen or specimens are distinctly visible on either side through 80 the transparent coverings 9—10. The specimen is thus not only displayed to advantage, but it is also protected from dust, insect pests, and danger of breakage or destruction. It can, furthermore, be easily 85 filed away in the drawers of a card index system or transported through the mail, when desired.

Further modifications of the pin are 90 shown in Figs. 1, 3 and 6. Instead of depending entirely on the points of the pin to hold the insect in place, the sides of the pin for a distance from the point may be corrugated as at 12, see Fig. 6, to render clasping 95 of the body more firmly, and to give a greater purchase to the supporting and sustaining power of the pin. In some instances, the inwardly projecting pin point may be entirely eliminated by providing two pins 13 and 14 (see Figs. 1 and 4) one of which 100 extends over the top surface of the wings, while the other extends under. The pressure of the pins against each other will hold the insect firmly in place.

In Fig. 7 another modification known as 105 "butterfly jewelry" is shown. This consists

of a band 15 of gold, or other metal, in which two oval glass disks 16 are secured and between which the butterfly is positioned. The pin may in this instance be soldered to the inner edge of the band.

We wish it understood that various changes in form, proportions and minor details of construction may be resorted to within the scope of the appended claims, and 10 that we do not wish to limit ourselves to the specific design and construction here shown.

When mounting larger butterflies and moths it is sometimes necessary to support the wings by pressing them up against the 15 under surface of the glass. A pin shaped substantially as shown in Fig. 8 is preferably employed for large specimens. In other instances, a plurality of pins may be used as shown in Fig. 9.

20 Having thus described our invention what we claim and desire to secure by Letters Patent is—

1. An entomological pin comprising two 25 legs of wire joined at the base and terminating in inwardly bent points.

2. An entomological pin comprising two 30 parallel legs of wire joined at the base and terminating in inwardly bent points, and corrugations formed on said legs and extending a distance from the points.

3. In a mount of the class described, the 35 combination of a pair of card-board sections having registering openings formed therein, a pin secured to said cards extending part way into the opening formed between the registering cards upon which the specimen

is secured, and a transparent closure covering said opening.

4. In a mount of the class described, the 40 combination of a pair of card-board sections having registering openings formed therein, a specimen positioned in the opening formed between the registering cards, and a supporting member secured between the cards extending part way into the opening to support the specimen.

5. An entomological mount comprising a 45 holder having an inclosed space formed therein for the reception of a specimen, and a supporting member extending part way 50 into the inclosed space to support the specimen.

6. In a mount of the class described, the 55 combination of a pair of card-board sections having registering openings formed therein, a specimen positioned in the opening formed between the registering cards, a transparent closure for said opening, and a radially disposed support extending into the opening 60 upon which the specimen is secured, said support being adapted to press the specimen against the under surface of the transparent closure.

In testimony whereof we have hereunto set our hands in the presence of two 65 subscribing witnesses.

XIMENA McGlashan.

LEONORA G. McGlashan.

CHARLES F. McGlashan.
